UNITED STATES PATENT OFFICE.

WALTER THOMAS WEAVER, OF NEW YORK, N. Y.

BINDING-MACHINE.

1,371,829.

Specification of Letters Patent. Patented Mar. 15, 1921.

Application filed June 16, 1920. Serial No. 389,530.

To all whom it may concern:-

Be it known that I, WALTER T. WEAVER, a citizen of the United States, and resident of the city of New York, borough of Manhattan, in the county of New York and State of New York, have invented a new and Improved Binding-Machine, of which the following is a full, clear, and exact description.

10 In connection with the photographic industry, and more particularly that branch of the same devoted to the manufacture of slides for projecting machines, it is well understood that the slide usually consists of a 15 glass plate upon which a representation of the image to be projected is displayed.

With a view of protecting this representation which may be in the nature of a sensitized surface or coloring, it has been customary to superimpose a second cover glass over the first plate, these two members being subsequently attached one to the other.

This attachment has been effected by utilizing adhesive strips, which were applied so that they enveloped the side edges and the upper and lower faces, adjacent their side edges of the members thus formed. This strip has thus permitted the forming of a single unit of the plate bearing the sensitized or other image carrying surface, and the cover glass aside from the fact that any rough edges which may have existed have been covered, so that the fingers of the operator were not likely to become 35 cut.

Applying the strips to the side edges of these units has been at best but tedious work, in that it has been necessary to carefully hold the two glass plates in superimposed condition, and to apply the adhesive strip with great caution, so that it might envelop all edges of the unit.

Aside from the great amount of time involved in correctly applying this tape, it 45 has been found the tape quite often is positioned in an irregular manner.

With this in mind, I have constructed a binding machine which is more particularly adapted for use in connection with the projection machines aforescribed, although the same might readily be used to bind the edges of any square member desired, and by means of which the edges of the plates or units will be quickly and evenly covered 55 with the adhesive binding element.

Reference is had to the attached sheets

of drawings as illustrating one practical embodiment of my invention, and in which drawings,

Figure 1 is a plan view of a machine constructed in accordance with my invention.

Fig. 2 is a sectional side view along the lines 2—2 of the same.

Fig. 3 is a sectional end view taken along the lines 3—3 of Fig. 1.

Fig. 4 is a further sectional view taken along the lines 4—4 of Fig. 1, and

Fig. 5 is a sectional view taken along the lines 5—5 of this figure.

Fig. 6 is a side view of the folder or binder.

Referring now more particularly to Figs. 1 and 2, it will be seen that my binding machine conveniently includes a pair of base members 10 which have secured to their upper faces, and adjacent one of their ends, the longitudinally extending member 11. A second similar member is positioned above the upper faces and adjacent the opposite ends of said base members, as has been indicated by the reference numeral 12, it being noted, however, that this latter member is conveniently provided with any desirable adjusting and retaining means, such as lock pins 13, and thumb screws 14; the former 80 co-operating with the openings 15 formed in the upper faces of the base members 10, the latter being mounted upon bolts extending through slots 16 in the member 12 their inner ends being secured to the base members 10 for a purpose hereinafter more fully 90 specified.

From the foregoing it will be seen that the base portion of the machine provides a longitudinally extending groove or slide-way, between the inner edges of the members 11 and 12, the width of which may be varied by means of the securing and retaining media aforescribed.

A slidable projecting member rests in the 100 groove thus formed, the said member conveniently including a base 17 capable of being moved through the groove by any suitable means such as a handle 18 affixed to its outer end, and being retained therein by 105 any desirable type of guides 17'.

With a view of limiting the motion of the base 17, a pair of stops 19 are conveniently associated one with each of these ends, which stops contact with the side 110 edges of the rearmost base member, upon the base reaching its extreme retracted or

projected positions, indicated in dotted and full lines respectively in Figs. 1 and 2.

The slidably projecting member further includes a block 20, which is securely affixed to the base 17. It is to be noted that the block 20 is formed with a cutout portion above which clips 21 forming a clevis or other suitable securing means extend so that plates 22 may be gripped by means of 10 said block.

With a view of providing supporting means for the slides 22, rails 23 extend throughout the entire length of the base portion, and conveniently overlie the groove 15 formed therein, it being noted that the upper face of the block 20 extends in a plane substantially similar to the upper edges of the rails 23, which are affixed to the base of the machine by any suitable 20 means such as supporting legs 24.

It will be understood, by this construction, that the plates 22 may be positioned upon the inner ends of the rails 23 upon the base 17 being retracted to the position indicated in dotted lines, and that upon the slidable projecting member being moved, that this will result in one of the plate units 25 being moved forward along the rails 23.

The base 17 may now again be retracted, 30 and a second plate brought to rest upon the rails 23. Upon the base and block 20 again being projected, the last named plate unit will be made to slide along the rails 23, and by virtue of the fact, as has been shown in 35 Figs. 1 and 2, that the forward edge of the same will bear against the rear edge of the first mentioned plate, this projection will serve to move the latter also.

Now with a view of taping the edges of 40 the plate units, rolls of tape 25 are provided, which rolls may be mounted in any desired manner, as for instance upon brackets 26. The tape 25 passes, subsequent to its withdrawal from the roll between moistening 45 rollers 27 and through guides 28, which serve to cause the same to assume a position transverse to the position originally occupied by the same.

Adjustably mounted upon the upper faces 50 of the members 11 and 12, such as for instance, by means of eccentrics 29, are rollers 30 having their edges preferably covered with any suitable resilient material, such as soft rubber, it being noted that these rollers, as has been clearly shown in Fig. 3, conveniently include a groove portion extending adjacent to the side edges of the units 22.

To the rear of the rollers 30, and extending in the same plane are pulleys 31 of any 60 desired type, which pulleys conveniently include rubber covered faces, and a groove portion at an angle more acute than the groove part of the rollers 30, as has been clearly shown in Fig. 4. It is to be noted 65 that the pulleys 31 are rotatably mounted

upon standards 32 of any desired type, and secured to the upper faces of the members 11 and 12 respectively, so that a rolling contact will be afforded, serving to fold the tape and hold the slide to the track.

My machine further includes folders, comprising a tapering groove portion 33, and a pair of spring fingers 34 extending above and below said folders, and terminating at intimate contact adjacent the most restricted portion of the same, a pivot point being conveniently provided for each of these members, which are positioned one to each side of the rails 23, such pivot including a suitable post 35 adapted to be engaged by 70 the adjustable retaining member 36. The retaining members 36 each conveniently mount one end of a spring 37, the opposite ends of which bear against the folders, and serve to swing the inner ends of the latter 75 inwardly, stops such as 38 being provided to limit the amount of this swinging motion.

It will now be understood that the slides 22 may be projected through the machine upon the rails 23 in the manner aforescribed, and with a view of applying tape to the same, the tape is conveniently passed around each of the rollers 30. It will now be understood that upon each slide being 90 projected the tape 25, by virtue of its adhesive qualities will be caused to contact and be applied to the edges of the slides as they pass between these rollers in the manner 95 shown in Fig. 3.

It will be seen that this action, although 100 serving to apply the tape to the side edges of the slides, will not cause the side edges and adjacent portions to be completely enveloped, and with this in view, the pulleys 31 have been provided, which serve, as has 105 been illustrated in Fig. 4, to bend the tape 25 to assume an enveloping position, and hold the slides down upon the track 23.

A further projection of the slides thus manipulated will cause the side edges of the same to pass into the folders by means of 110 which the tape will be pressed into contact with the faces of the plate unit, this action being further insured by means of the spring fingers 34.

It will be understood that the actions aforescribed will serve to produce the result desired, but it will be appreciated 115 that the tape might not be in as intimate contact with the plate units as would prove to be desirable, to insure the prevention of any loosening of the same from its applied position, and with this in view, I conveniently provide the roller group illustrated, which serves to press the tape into such intimate contact with the parts to be bound that any danger of a loosening of the same is precluded.

Referring now more particularly to Fig. 5 it will be seen that this roller group pref- 130

erably includes two pairs of vertically extending rollers 39, rotatably secured to the inner side edges of the members 11 and 12 respectively, it being noted that these rollers 5 over-lie and under-lie the plane occupied by the slide units during their travel over the upper edges of the rails 23. Rollers 40 are rotatably mounted within the members 11 and 12, and have their peripheries extending to a point adjacent the side edges of the plate unit.

By virtue of the fact that all of these rollers are covered with an elastic material, as has been indicated at 41 in Fig. 5, the tape 15 subsequent to its having been applied to the proper position upon the plate units will be firmly pressed into intimate contact with the same upon the slide passing through the roller group aforescribed, so that any 20 danger of the same becoming removed is precluded.

From the foregoing it will be understood that I have constructed a binding machine which shall be capable of applying tape to the 25 longitudinal edges of slides. Now with a view of applying tape to the side edges of the same it will readily be appreciated that any desirable number of plate units may be projected through the machine and 30 subsequently separated one from the other. The member 12 is now moved outwardly by virtue of the adjusting and securing members supplied for this purpose, so that a groove of greater width is presented, it being 35 noted that one set of rollers 30, roller groups 39 and 40, and one of the pulleys 31 will, by virtue of the fact that they are carried by this member, move with the same.

The plates may now be rested one at a 40 time upon the forward ends of the rails 23, and projected through the machine by means of which tape will be applied to the side edges of these plate groups, so that a series of completely taped plates are presented at the rear or delivery end of the 45 machine.

From the foregoing it will be appreciated that I have constructed a binding machine by means of which tape may be applied to 50 both the longitudinal and side edges of plates or other square plate members to be bound, which tape will be speedily and uniformly positioned in the proper manner.

Obviously numerous modifications of 55 structure might readily be resorted to without in the least departing from the spirit of my invention.

Having thus described my invention what I claim as new and desire to secure by Letters Patent is as follows:—

1. A binding machine, including a base portion, a track attached thereto, members secured to said base portion, tape applying means associated with each of said members 65 and extending to a point adjacent said track

and in an equal plane thereto, and means permitting a moving of one of said members for varying the space existent between said tape applying means.

2. A binding machine, including a base 70 portion, a track attached thereto, members secured to said base portion, means for projecting plates between said members, and tape applying means attached to each of said members and extending to a point adjacent 75 said track and in an equal plane thereto whereby to apply tape to opposite edges of a plate simultaneously upon the same being passed between said members.

3. A binding machine, including base portions, a track attached thereto, a member extending between said base portions and being secured to the same, a further member extending between said base portions, said last mentioned member being slidably 80 positioned thereon, tape applying means carried by each of said members and extending to a point adjacent said track and in an equal plane thereto, and means for projecting slides between said tape applying means. 85

4. A binding machine, including a base portion, rails overlying said base portion, a 90 slidable projecting member positioned upon said base portion, tape applying means associated with said base portion and extending to each side of said rails, said slidable projecting member being adapted to move slides through said tape applying means whereby to simultaneously attach said tape to opposite edges of said slides. 100

5. A binding machine, including a base portion, rails overlying said base portion, a 105 slidable projecting member positioned upon said base portion, tape applying means associated with said base portion and extending to each side of said rails, said slidable projecting member being adapted to move slides through said tape applying means, and a clevis associated with said slidable projecting member for gripping the rear edge of 110 one of said plates.

6. A binding machine, including a base portion, rails overlying said base portion, rollers adjacent the forward end of said rails, each of said rollers being formed with 115 a groove presenting an obtuse angle, pulleys to the rear of said rollers, each of said pulleys presenting a groove of a more acute angle than the groove of the rollers, folders to the rear of said pulleys, a roller group to 120 the rear of said folders, and means for projecting slides positioned upon said rails between said rollers, pulleys and roller group.

7. A binding machine, including a base portion, rails overlying said base portion, 125 rollers adjacent the forward end of said rails, said rollers being formed with a groove presenting an obtuse angle, pulleys to the rear of said rollers, said rollers presenting a groove of a more acute angle than 130

the groove of the rollers, folders to the rear of said pulleys, a roller group to the rear of said folders, means for projecting slides positioned upon said rails between said rollers, pulleys and roller group, said rails and pulleys being covered with a resilient material.

8. A binding machine, including a base portion, rails overlying said base portion, rollers adjacent the forward end of said rails, said rollers being formed with a groove presenting an obtuse angle, pulleys to the rear of said rollers, said rollers presenting a groove of a more acute angle than the groove of the rollers, folders to the rear of said pulleys, a roller group to the rear of said folders, means for projecting slides positioned upon said rails between said rollers, pulleys and roller group, said folders presenting a converging groove.

9. A binding machine, including a base portion, rails overlying said base portion, rollers adjacent the forward end of said rails, said rollers being formed with a groove presenting an obtuse angle, pulleys to the rear of said rollers, said rollers presenting a groove of a more acute angle than the groove of the rollers, folders to the rear of said pulleys, a roller group to the rear of said folders, means for projecting slides positioned upon said rails between said rollers, pulleys and roller group, said folders

presenting a converging groove, and spring fingers mounted upon said folders, the ends of said fingers contacting with one another adjacent the point of greatest constriction of said groove.

10. A binding machine, including a base portion, tape rollers secured to said base portion, tape moisteners contacting with said tape subsequent to its withdrawal from said rollers, rails extending above said base portion, means for projecting slides across said rails, adjustable rollers extending adjacent said rails and being adapted to receive said tape subsequent to its moistening, pulleys extending at a plane equal to that of the rollers, and means for forcing the tape into intimate enveloping contact with the side edges of said slides.

11. A binding machine, including a base portion, rails overlying said base portion, a slidable projecting member positioned upon said base portion, tape applying means associated with said base portion and extending to each side of said rails, said slidable projecting member being adapted to move slides through said tape applying means whereby to attach tape to the opposite edges of said slide simultaneously, and means for limiting the motion of said slidable projecting member.

WALTER THOMAS WEAVER.
